TRAY FOR RELEASABLY ENGAGING A RAZOR AND A BLADE CARTRIDGE DISPENSER

Martin Glaberson, Stratford, Conn., assignor to
Warner-Lambert Company, Morris Plains, N.J.

Filed Mar. 18, 1974, Ser. No. 452,173

Term of patent 14 years

Int. Cl. D9—03

U.S. Cl. D9—186

Fig. 1

Fig. 2

Fig. 3

Fig. 4

Fig. 5

Fig. 6

FIG. 1 is a top plan view of a tray for releasably engaging a razor and a blade cartridge dispenser showing my new design;

FIG. 2 is a bottom plan view thereof;

FIG. 3 is a side elevational view thereof;

FIG. 4 is an elevational view of one end thereof;

FIG. 5 is an elevational view of another end thereof; and

FIG. 6 is a top perspective view thereof.

The side view not shown is a mirror image of FIG. 3.

I claim:

The ornamental design for a tray for releasably engaging a razor and a blade cartridge dispenser, as shown and described.
